U.S. Cl. D6—113

Fig. 1

Fig. 2

Fig. 4

FIG. 1 is a perspective view of a rack for crib accessories or the like showing my new design;

FIG. 2 is a front elevational view thereof;

FIG. 3 is a right end elevational view thereof, the left end being a mirror image thereof; and

FIG. 4 is a top plan view thereof.

The rear and bottom of the article are substantially plain and unornamented. The portion of a crib shown in broken lines in FIG. 1 is for illustrative purposes only and forms no part of the claimed design.

I claim:

The ornamental design for a rack for crib accessories or the like, substantially as shown and described.
